TRAFFIC SIGNAL SYSTEM

Walter M. Jeffers, Syracuse, N. Y., assignor to
 Crouse-Hinds Company, Syracuse, N. Y., a corporation of New York

Application July 1, 1937, Serial No. 151,476

2 Claims. (Cl. 177—337)

This invention relates in general to traffic signal systems, and more particularly to such a system embodying means operable, in the event one of the lights in the signal becomes burned out, to disconnect the signal from regular operation, and to display either a steady or a flashing caution signal. Frequently, the lamp or bulb in the green or red signal burns out, and when the lamp in the red signal burns out considerable confusion to traffic results until persons in charge of the signaling system have had an opportunity to replace the burned out bulb. This confusion results due to the fact that traffic on one street receives a green or go signal, and the traffic on the other street receives no signal and often passes into the intersection, and this situation makes for collisions and serious accidents.

This invention has as an object a particularly economical and simple arrangement whereby upon one of the signal lights being burned out, a steady caution signal, or preferably a flashing caution signal, will be displayed to traffic.

In describing the invention, I make particular reference to the embodiment disclosed in the accompanying drawing which represents an across the line, schematic diagram of a signal system for one intersection embodying my invention. However, at the close of the description it will be obviously apparent to those familiar with the art that my invention may be also practised by making numerous changes in the wiring or hook-up of the apparatus.

In the drawing, the signals MG, MR and MA designate respectively the green, red and amber signals arranged to direct traffic on the main street of the intersection, and the signals CG, CR and CA designate the green, red and amber signals directing traffic on the cross street.

On streets which pass through the intersection, the signals are displayed in both directions on the street, and it is conventional to employ a separate bulb or lamp for each direction. Accordingly, the signals above referred to on the drawing each employ two bulbs being grouped together for simplicity in the drawing. These signals are successively and repeatedly displayed through regular traffic cycles after the manner well known to those familiar with the art. The successive and repeated display of the signals may be accomplished by any suitable cycle timer mechanism.

As here shown, the shaft 10 is constantly rotated by motor 11 which includes driving coil 13 connected to the feed wire 14 and the common return wire 15 through wires 16, 17. A plu-

rality of cams 18, 19, 20 and 21 are secured to the shaft 10 and rotatable therewith, and are arranged to actuate the movable members 22, 23, 24 and 25 of switches which include complementary stationary members 26, 27, 28 and 29. 5 The motor, cams and switches constitute a cycle timer for successively and repeatedly energizing the respective signal circuits.

The timer further includes a flashing switch comprising contacts 30, 31, the movable contact 10 30 being operated by star wheel 32 secured to shaft 10. The points of the star wheel 32 are arranged so as to actuate the movable element 30 at comparatively frequent intervals during rotation of the shaft 10. The stationary member 31 is energized by wire 16.

The switch elements 22, 26 control the circuit energizing the main street green and cross street red signals. Each of the stationary members 26, 27, 28 and 29 are energized from the feed wire 20 14 by wire 35, movable contact 36, stationary contact 37, wire 38. When the movable member 22 is actuated into engagement with stationary member 26, a circuit is completed through wire 39, coil of relay 40, wire 41, cross street red signal, wires 42, 43, to common return 15. A circuit is also completed through the main street green signal through wire 44 and common return wire 45.

Relay 40 is so designed or constructed as to 30 actuate its movable contact 46 by current flowing through both of the lamps in the cross street red signal. However, if either one of these lamps should burn out, the current flowing through the remaining lamp is not sufficient to cause movement of the armature 46, and permits it to move into engagement with stationary contact 47. The armature 46 is connected to the wire 39, and when the armature 46 is in engagement with contact 47, a circuit is completed through coil 40 49 of a thermal switch, the opposite leg of which is connected to the common return wire through wires 50, 51, 43. When coil 49 is energized, movable member 54 of thermal switch is moved into engagement with contact 55 establishing a circuit through the coil of relay 56, through wires 35, 48, 51, contacts 54, 55, wire 58, relay 56, wire 43, to the common return. When relay 56 is energized, its armature 36 is moved out of engagement with stationary contact 37 thus breaking 50 the feed circuit to the timer switches, and is moved into engagement with stationary contact 59. Inasmuch as armature 36 is energized from the feed circuit through wire 35, a stick circuit is established for relay 56, through wire 55

68, contacts 61, 62 of the manually operable switch or push button 63, wire 64. When armature 36 is moved into engagement with contact 59, a circuit is also completed through the 5 coil of relay 65, this circuit being established through wires 60, 68 and wires 69, 43, to the common return. The function of relay 64 will be hereinafter explained.

A circuit parallel to that previously described 10 is also established through the cross street green and main street red signals. This circuit is controlled by elements 23, 27 of the timer switch, and when these elements are moved into engagement by cam 19, a circuit is established through 15 wires 70, 71, through the coil of relay 72, wire 73, main street red signal, wire 45, to the common return. A circuit is also established through the cross street green signal by wire 74, wires 42, 43, to the common return. Armature 20 75, associated with relay 72, is connected to the wire 70. The relay 72 is of similar design and construction as relay 40. That is, when either 25 of the lamps in the main street red signal burn out, armature 75 is released or dropped into engagement with stationary contact 78. Accordingly, a hot feed is established through wire 79 to coil 80 of the second thermal switch, the opposite leg of the coil 80 being connected to the common return through wires 51, 43. When 30 coil 80 is energized, member 76 is moved into engagement with contact 81, and a circuit is then established through relays 56, 64, as previously described.

Normally, the main street amber signal MA is 35 energized by switch elements 25, 29, this circuit being established through wires 82, contact 83, armature 84, wire 85, through the main street amber light to the common return wire 15 by wire 45. Also, in normal operation, the cross 40 street amber signal CA is controlled by the switch elements 24, 28, the circuit being through wire 86, contact 87, armature 88, wire 89, through the cross street amber light, wires 42, 43, to the common return.

45 It will be observed, from the description thus far, that upon the failure of either lamp in the main street red signal, or cross street red signal, relay 65 becomes energized, causing the armatures 84, 88, associated therewith, to move out 50 of engagement with contacts 83, 87, and into engagement with contacts 90, 91. This effects deenergization of the two amber circuits, and inasmuch as the contacts 90, 91 are connected with the movable element 30 of the flasher switch through wires 92, 93, the amber signals are shifted from the control of cams 20, 21, and displayed in flashing sequence by the operation of star wheel 32 and switch elements 30, 31. This condition will maintain until the burned

out light or lights are replaced, and the manually operable switch 63 is opened.

The purpose of the manual switch or push button 63 is to release the stick circuit of relay 56. That is, after the attendant has replaced the burned out bulb, the switch 63 is momentarily opened to deenergize the relay 56 and permit armature 36 to drop into engagement with contact 37.

The purpose of the thermal switches 54, 76 is 10 to permit relay 40 to move armature 46 out of engagement with contact 47 without energizing relays 56, 65 when the switches controlled by cams 18, 19 are initially closed. That is, due to the fact that armatures 46, 75 are energized by 15 wires 39, 70, relay 56 might be energized sufficiently to actuate the armature 36 and close the stick circuit for relay 56 and energize relay 65. The thermal switches 54, 76 are so designed and adjusted as to close into engagement with contacts 55, 81 four or five seconds after their respective coils 49, 80 have been energized.

What I claim is:

1. A traffic signaling system including a plurality of signal circuits, each of said circuits including a signal light and a switch, a timer operable to successively and repeatedly actuate said switches, a flasher switch, a feed circuit for said flasher switch, a feed circuit common to said first mentioned switches including means normally connecting said feed circuit to said switches and operable to disconnect the feed circuit from said switches, certain of said signal circuits including means normally connecting the same to certain of said first mentioned switches, and being 35 operable to disconnect said caution signal circuits from said first mentioned switches and to connect the same to said flasher switch, certain other of said signal circuits including means operable, upon failure of the signal light in said 40 other circuit, to effect operation of said means in said feed circuit, and to effect operation of said means in said first mentioned signal circuit.

2. A traffic signal system including a go signal circuit, a stop signal circuit, and a caution signal circuit, each of said signal circuits including an electric light illuminated when said circuit is energized, a timer including a switch connected in each of said signal circuits, a feed circuit common to all of the switches of said timer, 50 and said timer and switches being operable to successively energize said signal circuits, said stop signal circuit including means operable, upon failure of the light in said circuit, to effect deenergization of said feed circuit to the timer 55 switches and to energize said caution signal circuit.

WALTER M. JEFFERS.
